UNITED STATES PATENT OFFICE

125,692

DESIGN FOR A DRAPERY FABRIC

Harry Josephson, New York, N. Y.

Application October 29, 1940, Serial No. 96,158

Term of patent 3½ years

To all whom it may concern:

Be it known that I, Harry Josephson, a citizen of the United States, residing at New York, in the county of New York and State of New York, have invented a new, original, and ornamental Design for a Drapery Fabric, of which the following is a specification, reference being had to the accompanying drawing, forming part thereof.

The figure is a plan view of a drapery fabric showing my new design.

I claim:

The ornamental design for a drapery fabric, as shown,

HARRY JOSEPHSON,
